UNITED STATES PATENT OFFICE.

HENRY CHARLES URBANER, OF NAPERVILLE, ILLINOIS.

POWER-HAMMER.

1,355,291.

Specification of Letters Patent.

Patented Oct. 12, 1920.

Application filed May 19, 1919. Serial No. 298,024.

To all whom it may concern:

Be it known that I, HENRY CHARLES URBANER, a citizen of the United States, residing at Naperville, in the county of DuPage, State of Illinois, have invented a new and useful Power-Hammer; and I do hereby declare the following to be a full, clear, and exact description of the invention, such as will enable others skilled in the art to 10 which it appertains to make and use the same.

The invention relates to power hammers and has for its object to provide a hammer of this character which is simple in construction, small and compact, thereby allowing the use of a power hammer in small establishments.

A further object of the invention is to provide a power hammer wherein the hammer head is reciprocated by means of a pitman rod, said pitman rod being actuated by a rotating wheel, which actuation of the pitman rod causes the hammer head to be moved in a vertical plane by means of two 25 cross heads carried by the frame of the machine.

A further object is to provide the hammer head with a spring actuated resilient means whereby said spring will increase the percussive blows of the hammer head as the hammer head reciprocates.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit 40 of the invention.

In the drawings:

Figure 1 is a view in side elevation of the power hammer.

Fig. 2 is a front elevation of the same.

Fig. 3 is a vertical sectional view taken on line 3—3 of Fig. 2.

Fig. 4 is a plan view of a rotating tool carrying turret, which is used in conjunction with the hammer.

Fig. 5 is a sectional view taken on line 5—5 of Fig. 4.

Fig. 6 is a horizontal sectional view taken on line 6—6 of Fig. 5.

Referring to the drawings, the numeral 55 1 designates a frame, which frame is preferably formed from angle iron as shown.

If desirable, however, this frame may be formed from a casting. The upper end of the frame 1 is provided with a bed plate 2 which bed plate 2 extends around and down the front face 3 of the frame and terminates preferably within the throat 4 of said frame. Secured to the bed plate 2 by means of bolts 5 are upstanding bracket arms 6 and rotatably mounted in said bracket arms are 65 shafts 7 and 8. A pulley 9 is secured by means of a pin 10 to the shaft 7, said pulley being adapted to receive a belt which may lead to any suitable source of power. One side of the pulley 9 is provided with a 70 conical depression 10 forming a clutch member, which clutch member is adapted to be coöperated with by the slideable clutch member 11 which is feathered on a key 12 of the shaft 8, there being a coil spring 13 disposed between the pulley 9 and the slideable clutch member 11, which spring normally keeps the clutch member out of engagement with the conical depression 10 of the pulley thereby allowing the pulley to rotate at all 80 times without transmitting power to the shaft 8. A clutch actuating yoke 14 is adapted to slide the clutch member 11 on the shaft 8. This yoke 14 is secured on a shaft 15 which shaft 15 is carried by lugs 85 16, in which lugs the shaft 15 is rotatably mounted. One end of said shaft is provided with an arm 17, said arm being secured to the rockable shaft 15 and has its other end connected to a connecting rod 18, the lower 90 end of said connecting rod being in turn connected to a foot lever 19, which foot lever is pivoted at 20 to the frame of the machine. It will be seen that by depressing the foot lever 19 the clutch member 11 will be 95 forced into engagement with the conical depression 10, in the pulley 9 against the expansive action of the coil spring 13, thereby imparting a revoluble movement to the shaft 8. However, when the foot is removed from 100 the foot lever 19 the expansive action of the coil spring 13 will force the clutch as a whole out of operation, thereby stopping the rotation of the shaft 8.

Keyed to the outer end of the shaft 8 is 105 a fly wheel 20, said fly wheel being provided with a wrist pin 22, to which wrist pin the upper end of a pitman 23 is connected. The lower end of the pitman 23 is pivotally connected as at 24 to an auxiliary 110 cross head 25, said cross head 25 being vertically slidably mounted in cross head guides

26 carried by the front face of the frame. The lower end of the cross head 25 is provided with a depression 27, which depression is adapted to receive and have clamped therein by means of bolts 28 a piston rod 29. The piston rod 29 is in a vertical position and has its lower end disposed within a cylinder 30 and secured as at 32 to a coil spring 33, said securing point being at a point intermediate the ends of said coil spring, however it has been found preferable to secure the lower end of the piston 29 to the coil spring, at a point below the center thereof.

15 The cylinder 30 is preferably lined with a brass lining and the cylinder as a whole having its upper end closed by means of a cap 35 which may be threaded or otherwise secured thereto. The object of the brass lining in the cylinder is to prevent wearing of the spring when the machine is in operation and the cylinder is reciprocating rapidly on the end of the piston rod 29. The cylinder 30 is integrally secured to a cross head 36, which cross head is vertically slidably mounted in cross head guides 37, said guides 37 being in vertical alinement with cross head guides 26. This alinement of cross heads 25 and 36 insuring the vertical movement of the piston 29 and the cylinder 30 also the elimination of any wabbling of the parts. The lower end of the cross head 36 is provided with the dove-tail slot 38 in which slot various types of metal forming tools 39 may be held by means of set bolts 40.

It will be seen that as the cross heads are reciprocated that the cross head 36, which carries the metal forming tool will be moved upwardly and downwardly and that the resilient connection between the lower end of the piston rod 29 and the coil spring within the cylinder, that the percussive blows of the metal forming tool may be increased or diminished in force according to the speed of rotation of the pulley 9. It will also be seen that as the metal that is being worked cools, that the length of the stroke of the metal forming tool need not be varied, for the reason that variations of this character are taken up in the coiled spring.

The tool carrying turret comprises a base 41 which base has an upwardly extending projection 42 on which the object to be formed by the power hammer is adapted to be placed. The base 41 is provided with a chamber 43, and rotatably mounted in a vertical position is a bearing 44 of said base, and 45 is a shaft, which shaft 45 has keyed as at 46 thereeto a revoluble tool turret 47, which 60 tool turret comprises arms 48 having tool holding means 49 at the ends thereof. The turret 47 is adapted to be rotated by hand and various tools of various shapes which are carried in the tool holding ends 49 of the 65 arms 46, may be brought into registration

with the article to be formed which article is disposed upon the upward projection 42 as clearly shown in Fig. 1 of the drawings. Slidably mounted on a key 50, of the shaft 45 is a clutch cone 51, the upper end of said clutch cone being adapted to coöperate with the conical depression 52 of the upper end of the chamber 43 of the base 41. A collar 52 is pinned as at 53 to the lower end of the shaft 45 and disposed between said collar 75 and the lower surface of the clutch cone 51 is a coil spring, which coil spring normally keeps the clutch cone 51 in engagement with the conical depression 52, thereby preventing the rotation of the shaft and the turret 80 47 carried thereby. A clutch cone operating yoke 55 is in engagement with said clutch cone and is provided with a downwardly extending arm 56, which arm 56 is pivoted at 57 to the foot operating lever 58, said foot 85 operating lever 58 being in turn pivoted at 59 to a lug carried by the base 41. It will be seen that by imparting a downward movement to the lever 58, that the yoke 52 will be forced downwardly, which downward 90 forcing of the yoke 54 will pull the clutch cone 51 out of engagement with the conical depression 52, thereby allowing the turret carried by the shaft 45 to be easily rotated by the hand of the operator until the proper tool is in position for use, when the proper tool is in position for use the pressure is relieved from the foot lever 58, thereby allowing the coil spring 54 to force the cone 51 upwardly into engagement with the conical 95 depression 52 which will maintain the tool carrying turret 47 in any position to which it may have been moved.

The invention having been set forth what is claimed as new and useful is:—

105

A power hammer comprising a frame, a rotatable shaft mounted in said frame, said rotatable shaft having a fly wheel secured to one of its ends, a pitman rod having one of its ends secured to a wrist pin carried by 110 the fly wheel, said pitman being pivoted to a vertically guided cross head, a vertically disposed hammer carrying rod detachably connected to the cross head, the lower end of said rod being centrally connected to a coiled 115 spring, which coiled spring surrounds the rod and extends below the end of said rod, said coiled spring being disposed in a vertically disposed chamber of a vertically guided hammer member, so that the hammer member is resiliently supported during a reciprocation of the rod and during a hammering operation.

In testimony whereof I have signed my name to this specification in the presence of 125 two subscribing witnesses.

HENRY CHARLES URBANER.
